Attorney

Patented Dec. 16, 1924.

UNITED STATES PATENT OFFICE.

SCOTT S. STEWART, OF RIVESVILLE, WEST VIRGINIA.

CHECK HOLDER.

Application filed January 7, 1924. Serial No. 684,820.

To all whom it may concern:

Be it known that I, SCOTT S. STEWART, a citizen of the United States, residing at Rivesville, in the county of Marion and 5 State of West Virginia, have invented certain new and useful Improvements in Check Holders, of which the following is a specification.

This invention relates to article holders, 10 and more particularly to check holders for miners' checks and the like.

An object of the invention is the provision of a check holder that may be worn on the belt of the user.

15 A further object of the invention is to provide a check holder in which accidental displacement of the checks is reduced to a minimum.

A further object of the invention is the 20 provision of a check holder of simple construction and relatively few parts.

In the accompanying drawings, I have shown one embodiment of the invention. In this showing:

25 Figure 1 is a perspective view showing a check on the holder,

Figure 2 is a central vertical sectional view,

Figure 3 is a perspective view of the base 30 of the check holder with the resilient member removed,

Figure 4 is a similar view of the resilient member,

Figure 5 is a horizontal sectional view on 35 line 5—5 of Figure 2, and,

Figure 6 is a similar view on line 6—6 of Figure 2.

Referring to the drawings, the reference 40 numeral 1 designates the base of the check holder which is preferably formed of a sheet of metal and folded to provide front and rear parallel walls 2, a bottom 3, and a top wall 4. The ends of the sheet are extended forwardly and arranged one above the other, as indicated at 5. These extended 45 portions may be secured to each other in any suitable manner, as by rivets. One end is extended downwardly, forming a flange 6 parallel to the body portion which is adapted to serve as a stop for the resilient member. Adjacent the bottom of the front, the base is provided with two cut out portions 7 and between these cutout portions and the top, there is provided a second pair of cut 55 out portions 8 having openings 9 formed therein.

The resilient member preferably consists of a single piece of resilient wire comprising a loop 10, the end of which is offset, as at 11, and arranged behind the flange 6. The 60 loop extends downwardly below the supporting member when in position and the arms of the loop are then extended at right angles, as indicated at 12. These parallel arms are then extended upwardly, as at 13, to a 65 point adjacent the bottom of the base and are again extended horizontally, as at 14, to the front of the base. The arms are then extended upwardly parallel to each other, as at 15, and the cut out portions 7 of the base 70 are curled around the arms, as at 16. The ends of the arms are offset in opposite directions, as at 17, and these offset portions are received in the openings 9.

The operation of the device will be apparent from the foregoing description. A check 75 is placed on the holder or removed by pressing inwardly on the loop to space it from the flange 6. In normal position, the check is disposed on the horizontal portions 12 of 80 the resilient member beneath the base. By extending the horizontal portions 12 rearwardly from the loop 10, a considerable distance, a construction is provided which will 85 support a plurality of checks. The cut out portions 8 not only serve as a support for the resilient member but further serve to prevent accidental movement of the checks upwardly on the loop and thus prevent accidental displacement. 90

It is to be understood that the form of my invention herewith shown and described is to be taken as a preferred example of the same, and that various changes in the shape, size, and arrangement of parts may be resorted to without departing from the spirit 95 of the invention or the scope of the subjoined claims.

I claim:

1. In a device of the character described, 100 a base member adapted to be arranged on the belt of the user, and a resilient member formed of a single piece of wire having its ends secured to one side of the base, the arms being extended downwardly beneath the base, then forwardly a slight distance from said base, and then upwardly, forming a loop in front of said base.

2. In a device of the character described, 110 a base member adapted to be arranged on the belt of the user, the upper edge of said base being extended, a flange formed on said

extension, and a resilient member formed of a single piece of wire having its ends secured to one side of the base, the arms being extended downwardly beneath the base and bent upwardly to form a loop, said loop normally contacting with said flange.

3. In a device of the character described, a supporting member comprising a sheet of metal folded to fit around the belt of the user, said supporting member being provided with cut out portions in one face, and a resilient member formed of a single piece of wire having its ends received in said cut out portions, said supporting member being provided with a second pair of cut out portions adapted to be curled around the arms of said resilient member to retain said resilient member in position.

4. In a device of the character described,

a base adapted to be received on the belt of the wearer, a flange formed on the upper edge of said base, and a resilient member comprising a single piece of wire having its ends secured to said base, said resilient member being provided with a pair of substantially parallel arms extending downwardly to a point adjacent the bottom of the base, then extended beneath the base then extending in the opposite direction and then upwardly, the ends of said arms forming a loop normally engaging said flange.

In testimony whereof, I affix my signature in presence of two witnesses.

SCOTT S. STEWART.

Witnesses:

W. E. CATHER,
BESSIE BARTH.
